UNITED STATES PATENT OFFICE.

WILLIAM MARX, OF WAUWATOSA, WISCONSIN.

DESIGN FOR A PATTERN FOR CHAIR-BACKS.

SPECIFICATION forming part of Design No. 22,328, dated April 4, 1893.

Application filed January 31, 1893. Serial No. 460,484. Term of patent 3½ years.

To all whom it may concern:

Be it known that I, WILLIAM MARX, of Wauwatosa, in the county of Milwaukee and State of Wisconsin, have invented and produced a new and original Design for the Ornamentation of Chairs, of which the following is a description, reference being had to the accompanying drawing, which is a part of this specification.

In the drawing, A is the top cross bar of a chair back, on which my design is shown as carved or stamped.

The leading feature of the design is a ship of the class known as a caravel, and particularly the vessel called the Santa Maria with sails all set, sailing in water, on an elongated panel bounded by a frame or molding and circular representations of the Eastern and Western Hemispheres at the right and left respectively of the panels.

The design is intended to be carved or stamped and produced in relief on the top cross bar of a chair back.

The design is more particularly described as consisting of a vessel of the class known as a caravel, and particularly as the Santa Maria, the vessel in which Columbus made his first voyage of discovery, the vessel having

all its sails unfurled and being represented as sailing on water toward the left or west, the 30 vessel and the water being represented as on a panel B elongated horizontally and encompassed by a border, and at the right of the panel is a circle C on the field of which is represented in miniature the land and water 35 of what is known as the Eastern Hemisphere, and at the left of the panel is a circle D on the field of which is represented in miniature the land and water of what is known as the Western Hemisphere. The vessel is shown 40 at broadside sailing from the Eastern Hemisphere or Old World, toward the Western Hemisphere or New World. In the panel centrally below the vessel a space is provided adapted to receive a suitable inscription. 45

What I claim is—

The design for a pattern for the top cross bar of a chair back, substantially as shown and described.

In testimony whereof I affix my signature in 50 presence of two witnesses.

WILLIAM MARX.
